UNITED STATES PATENT OFFICE.

JOHN A. LEMMON, OF HILL GROVE, VIRGINIA.

BOOT OR SHOE.

SPECIFICATION forming part of Letters Patent No. 269,800, dated December 26, 1882.

Application filed October 9, 1882. (No model.)

To all whom it may concern:

Be it known that I, JOHN A. LEMMON, a citizen of the United States, residing at Hill Grove, in the county of Pittsylvania and State 5 of Virginia, have invented certain new and useful Improvements in the Manufacture of Boots and Shoes; and I do declare the following to be

a full, clear, and exact description of the invention, such as will enable others skilled in 10 the art to which it appertains to make and use the same, reference being had to the accompanying drawings, and to the letters and figures of reference marked thereon, which form a part of this specification.

15 The main obstacles which have heretofore prevented the successful manufacture of seamless shoes, either for the wholesale trade or to fill individual orders for personal use, have been, first, the labor required to work out the 20 wrinkles; secondly, the necessity for using "flaky" or unsubstantial leather, which, by reason of its having less strength and body, would lessen the amount of labor required in working out the wrinkles. The last, but perhaps not the least, objection was that the pattern cut out would not leave the upper in 25 shape for manufacture of any style of shoe required.

My invention, I have demonstrated from 30 practical experience, has overcome said objections; and it consists of an upper having the vamp, quarters, and heel in one piece, and having a piece cut therefrom to form the ankle-opening in substantially the form herein described and claimed, and shown in the drawings.

To avoid the objections hereinbefore stated, I have found it necessary in cutting the ankle-opening to dispense with right lines and to 40 make the depth of the opening nearly equal to its width, to have its sides curved outwardly and its ends inwardly, avoiding short curves or corners, which would centralize the wrinkles at such points. It is important to throw the 45 wrinkles as nearly equally at all points of the opening as possible, and yet have the opening the desired shape for formation in the finished shoe. This result is accomplished by my invention. If the sides of the opening are 50 straight, all the wrinkles form at the ends,

and vice versa. If a perfectly round cut were made, the wrinkles would of course form equally at all points; but such an opening would make the sides too low and the ends too high.

55

The shape of my pattern is such that it distributes the wrinkles better than any pattern heretofore known.

With my pattern I can make seamless shoes of any of the popular styles—as, for instance, 60 the buttoned gaiter, imitation buttoned gaiter, imitation tie gaiter, tie, laced, imitation laced gaiter, side-laced, side-laced imitation buttoned, side-laced imitation tie, &c.

Some of the advantages of my invention, 65 not before stated, are, first, by reason of the ends being gradually curved inwardly and extending from side to side the depth of the opening is increased by turning the inwardly-projecting parts outwardly, whereby I am enabled to cut a minimum quantity of leather 70 from the upper and utilize smaller pieces; secondly, by the better distribution of the wrinkles around the edges of the opening I am enabled to use strong and substantial leather, whereby when the upper is lasted and the inwardly-curved end pieces are drawn outwardly very 75 few wrinkles remain to be rubbed out.

The upper halves of two ordinary railroad T-rails placed together, treads outward, would 80 form a figure a transverse section of which would be substantially like the pattern made in accordance with my invention.

In the accompanying drawings, Figure 1 is a plan view of a shoe-upper embodying my invention. Fig. 2 is a shoe made after my improvement.

85 In carrying out my invention, I cut from the piece of leather or prospective upper A, by means of a pattern laid thereon, an opening, 90 B, for the insertion of the foot. This opening B, as will be observed more particularly by reference to Fig. 1, is approximately square in its general shape. In other words, its rear and forward edges or sides are curved inward 95 at the center at a moderate degree, as at a a', with the corners rounded or oppositely curved, as at b, while its sides are curved slightly out of a straight line outward, as at c c'. The piece B is further cut to cause it to assume substan- 100

tially the shape shown in Fig. 1, for attachment to the sole.

The upper can be made of either flaky or substantial leather, to which may be added by stitching or sewing on an added piece when it is desired to be used in making a gaiter or boot.

The waste piece removed from the upper can be utilized for making a fine quality of leather strings. The upper can also be ornamented by configurated stitching, an example of which is shown in the figures of the drawings.

I claim and desire to secure by Letters Patent—

1. An upper for a shoe or boot, made in one piece, substantially as herein shown and described, the ankle-opening having an inwardly-

projecting end, a' , and sides having a slightly outward curvature, as and for the purpose set forth.

2. The upper A, cut to assume substantially the shape shown, and having the ankle-opening B constructed with inward-projecting curved edges a a' at its rear and forward edges, and with slightly outward curved sides c , as shown and described, and for the purpose set forth.

In testimony whereof I affix my signature in presence of two witnesses.

JOHN A. LEMMON.
